UNITED STATES PATENT OFFICE.

FREDERICK CRAIG, OF SPRINGFIELD, OHIO.

GAME.

Application filed November 29, 1927. Serial No. 236,527.

This invention relates to a game, and the object of the invention is to provide a ball game which includes an inclined table or surface equipped with a series of pockets of different values.

In the accompanying drawings:

Fig. 1 is a top plan view of the table which I use in connection with my improved game.

Fig. 2 is a section on the line *a—a* of Fig. 1. Fig. 3 is an enlarged section of a portion of the table showing several of the pins which I employ to form the pockets.

Fig. 4 is also an enlarged section of a portion of the table showing a modification in the form of the pin.

Fig. 5 is a longitudinal section of a portion of the table showing one form of projecting the balls.

Fig. 6 is also a longitudinal section of a portion of the table showing a modified form of projector for the balls.

Referring to the drawings, 1 represents an inclined surface which in the present case is a table of rectangular form having enclosing sides 2 supported in inclined position by foldable legs 3 having foldable braces 4. The upper surface of the table is provided with a large centrally arranged pen 5 substantially of diamond shape, the walls of which are formed of a series of spaced apart pins 6 which are fastened in the table 1 preferably by providing each pin with a reduced portion 6' which projects through an aperture in the table and provided with a lower threaded end to receive a nut 7; a washer 8 being preferably inserted between the shoulder formed by the reduced portion and the upper surface of the table. At suitable intervals in the walls of this pen the pegs are discontinued to provide openings 9, 10, 11, 12, 13, 14 and 15 and at each angle of the pen there is formed by the pins circular pockets 17, 18, 19 and 20. Each circular pocket is provided with an opening indicated at 21, 22, 23 and 24, the pocket 18 being provided with an additional opening 25. On the upper portion of the table and in opposite sides of the center thereof are circular pockets 26 and 27, the pocket 26 having two openings 28, 29 and 29' and the pocket 27 having three openings 30, 31 and 32. Near the lower end of the table there are two more circular pockets 33 and 34 having openings 35, 36 and 37 and at the extreme lower end of the table there are three semi-circular pockets 38,

39 and 40. Also arranged substantially in the

center of the pen 5 is a pocket 41 having an opening 42.

The pins forming the walls of the pen and pockets are close enough together to prevent the passage therethrough of the balls which are employed in playing the game but at the openings the pins are spaced just far enough apart to permit the entry or exit of the balls.

Arranged more or less arbitrarily upon the table on the outside of the pen and the pockets are pins 43 which act as deflectors.

Extending upwardly from the lower end of the table at one side thereof to a point near the upper portion thereof is a strip 44 to form a runway for balls 45. One method of projecting the balls is illustrated in Fig. 5, and consists merely of a flexible tube 46 which can be inclined to the position shown so that when a ball 45 is placed in the tube it will acquire sufficient momentum to roll up the runway and then downwardly among the individual pegs and the pockets; the upper corners of the table being preferably rounded as indicated at 47 to act as deflectors for the balls.

In playing the game, the player is allowed to project successively a series of balls to the upper portion of the table, which will either find lodgement in the pockets or will escape the pockets and come to rest on the extreme lower end of the table. The pockets are given different values as noted and the total of the values of these pockets in which balls find lodgement constitute the result sought in playing the game.

In Fig. 6 is shown a modification in the form of projectors, in which a plunger 48 is employed which is slidably mounted in the lower enclosing portion 2 of the table and also in a block 49 fixed in the runway. A coiled spring 50 interposed between a collar 51 on the plunger and the part 2 of the table furnishes the means of projecting the ball after the operator has placed the spring under tension.

In Fig. 4 is shown a modification in which the pin is formed of a tube 52 to furnish a musical tune when the balls strike the pins. This pin in the present case is secured preferably by welding to an inner pin 6^a similar to the pins 6, attached to the table in a manner similar to the pins 6.

Having thus described my invention, I claim:

1. In a game of the character described, an inclined surface bounded by walls, a pen formed of spaced-apart pins on said surface,

- said pins at intervals being spaced sufficiently to form doors, a series of pockets formed in the walls of said pen also formed of spaced-apart pins and having doors 30
5. formed by spacing said pins, a plurality of other pockets formed from spaced-pins located about said pen, and a plurality of deflecting pins arranged in the space about said pen and pockets. 35
10. 2. In a game of the character described, an inclined surface bounded by walls, a diamond-shaped pen formed of spaced apart pins on said surface, said pins at intervals being spaced sufficiently to form inlet and 40
15. exit openings. 45
3. In a game of the character described, an inclined surface bounded by walls, a diamond-shaped pen formed of spaced apart pins on said surface, said pins at intervals being spaced sufficiently to form inlet and 50
20. exit openings, and a series of pockets formed in the wall of said pen and also formed of spaced apart pins and having inlet and exit openings formed by spacing said pins. 55
25. 4. In a game of the character described, an inclined surface and a plurality of pockets arranged on said surface, said pockets being formed of a series of spaced apart pins, said pins being spaced sufficiently in all of said
- pockets to form an inlet opening and also 30
being spaced in some at least of the pockets to form exit openings. 35
5. In a game of the character described, an inclined surface and a plurality of pockets arranged on said surface, said pockets being 40
formed of a series of spaced apart pins, said pins being spaced sufficiently in all of said 45
pockets to form an inlet opening and also being spaced in some at least of the pockets to form exit openings, and a plurality of deflecting pins arranged about said pockets. 50
6. In a game of the character described, an inclined surface bounded by walls, a central diamond-shaped pen formed of spaced apart pins on said surface, a pocket formed of spaced apart pins formed at each of the points of said diamond shaped figure, the pins of both the diamond shaped pen and of the pockets being spaced apart to form inlet and outlet openings for balls, a central pocket 55
formed of pins having an inlet opening arranged within said diamond-shaped pen, and a plurality of pockets formed of pins each having an inlet opening arranged beneath said diamond-shaped pen. 60

In testimony whereof I have hereunto set
my hand this 26th day of November, 1927.

FREDERICK CRAIG.
